UNITED STATES PATENT OFFICE.

WILLIAM H. MUNROE, OF MAPLEWOOD, MASSACHUSETTS.

SPINDLING PLUG FOR PAPER CORES.

No. 880,687.

Specification of Letters Patent.

Patented March 3, 1908.

Application filed June 3, 1907. Serial No. 377,110.

To all whom it may concern:

Be it known that I, WILLIAM H. MUNROE, a citizen of the United States, residing at Maplewood, in the county of Middlesex and State of Massachusetts, have invented certain new and useful Improvements in Spindling Plugs for Paper Cores, of which the following is a specification.

My invention relates to the application of plugs or spindle bearings to the ends of the tubular shells which, in many arts, serve as central cores for rolls of paper, cloth, or other materials in sheet form which are wound or spooled thereon.

For many reasons it is desirable that such cores be of the minimum weight consistent with the stress they may be called upon to stand in service, and hence non-metallic materials of a tough nature, for example paper, are frequently employed in the formation of the same.

Where the rolls formed around such cores as centers are of great weight, it is desirable, and often necessary, that the ends of the central cores of the rolls be provided with wear-resisting spindling plugs, adapted to serve as bearings for the central spindle about which the roll revolves as an axis when the material which it carries is being either spooled or unwound.

I am aware that metallic spindling plugs have hitherto been applied to the ends of tubular paper cores for this purpose, but such plugs have been usually attached thereto by pins, screws, or by means of instrumentalities of the like nature, passing through the paper core, and also engaging the plug. This method of attaching the plugs to the core ends is not satisfactory or permanent, as the stresses incident to service will cause said plugs in time to become loosened and to tear away from the ends of the core in spite of the attaching instrumentalities.

My invention aims to provide a construction whereby a preferably metallic spindling plug may be attached to the ends of tubular cores, preferably of non-metallic materials, in a manner insuring permanency of attachment as well as durability in service.

In the drawings, Figure 1 shows, partly in section, one end of a roll having a spindling plug attached thereto in accordance with my invention, as well as a portion of the spindle adapted to fit therein. Fig. 2 is a view of the outside end of the plug. Fig. 3 shows,

partly in section, the jacket preferably used in conjunction with the plug.

Referring to the drawings, 1, Fig. 1, represents one end of a tubular paper core. At 2 is the spindling plug, interiorly bored to receive the spindle 3. Said spindle 3 preferably has the collar 4 by which the spindle may be positioned longitudinally with respect to plug 2, and a pin or key 5 is provided, adapted to engage in slot 6 in plug 2, Figs. 1 and 2, and thereby to prevent the rotation of the spindle with respect to the plug.

For a portion of its length the plug is preferably exteriorly threaded, with a tapering thread of the woodscrew type. The diameter of the threaded portion of the plug at its inner end 7 is substantially equal to that of the interior of the paper core, in order to permit its being entered and screwed into the same. The depth of the threads is sufficient to insure the necessary tenacity of hold between the plug and the end of the core when it is screwed into the same.

Surrounding that portion of the core end which is in engagement the threaded portion of the plug and extending along the unthreaded length of the plug at 8, for a short distance, as far as the retaining groove 9, is the jacket 10. Said jacket, shown in its original condition in Fig. 3, is a cylindrical shell, preferably of thin, but strong and ductile, metal, so sized with relation to the core as to closely fit on the exterior of the same. The outside diameter of the jacket is preferably that of the plug 2 at its outside end 11, but in order to permit the jacket to extend over the plug to the retaining groove 9 the plug is small enough in diameter at 8 to permit the same to enter into the interior of the jacket. The retaining groove extends circumferentially around the plug where surface 8 ends, and it is of a depth to insure a diameter at the bottom of the groove somewhat less than that of the plug at 8.

The manner of attaching plug 2 to the end 1 of the paper core is as follows. The jacket is first slipped over the core end, enough of its length being left projecting past the same to reach to the retaining groove when the plug is put in place. Plug 2 is then inserted into the core end and is screwed home, the jacket meanwhile co-operating with the core in preventing the breaking or undue expansion of the core end under the expansive influence exerted by the screwing in of the plug. After the plug is

screwed up into place, the edge 12 of jacket 10 is beaded over or other wise forced into the retaining groove 9, and other supplementary grooves 13 and 14, or other indentations adapted to perform a similar function, are formed on the surface of the jacket, thereby firmly securing jacket 10 longitudinally with reference to the core end. This securing the jacket longitudinally with respect to both core end and the spindling plug is desirable not only because of the obvious increase of strength imparted to the whole construction by such a practice, but also because a jacket thus secured will prevent the unscrewing of the plugs from the core end if by mistake the plugs be subjected to a torsional stress tending to unscrew them from the core ends. The other end of the core may be fitted with a spindling plug in the same manner as just above described, and the core is then ready for use as a central core upon which material may be wound.

It is preferable that the plugs be made, one with a right- and the other with a left-hand thread, so that any torsional stress put upon said plugs will tend to tighten the same, and not to unscrew them. Furthermore since that portion of the core not surrounded by the jacket will be of slightly less diameter than the jacket, it may be advisable to build up said portion of the core by the addition of several layers of paper in order to insure a uniform diameter of the core throughout its length.

While I have above described a plug designed to engage the core end by means of threads of a considerable depth formed thereon, it is sufficient in many cases, especially those in which the core is subjected to a comparatively light duty, that the threads be of slight depth, or even wholly dispensed with; the plug in the latter case being merely driven into the core and held therein by friction alone.

In cases where a plug of the latter type is used the jacket is first placed in position around the core end as hereinbefore described, and the plug is then driven into position. When the plug is in place the jacket as before may be longitudinally fixed with relation to both plug and core end by circumferential grooves or other indentations, or by pins, rivets or the like. In many cases the frictional engagement between the surface of the core end and the jacket is sufficient to longitudinally fix the jacket with relation to the core end.

While I have more particularly described my invention with reference to paper cores fitted with metallic plugs I do not mean to confine myself in any way to the materials specifically stated.

Having described my invention, I claim as new and desire to secure by Letters Patent:

1. In combination with a tubular winding core, a spindling plug engaging with the interior of the end of said core, and a jacket, mechanically separate from said plug, surrounding said core end and longitudinally fixed with reference to plug and to core end. 70

2. In combination with a tubular winding core, a spindling plug adapted to engage with the interior of the end of the said core, and a jacket surrounding the said core end and plug lying therein, said jacket being in engagement with the said plug and having superficial indentations whereby it is longitudinally fixed with relation to the said core end. 75

3. In combination with a tubular winding core, a spindling plug provided with a retaining groove, and adapted to engage within the interior of the end of said core, and a jacket surrounding said core end and the plug lying therein, said jacket being in engagement with said plug, and having circumferential grooves 85 whereby the said jacket engages the core end.

4. In combination with a non - metallic tubular winding core, a spindling plug having a portion of its length exteriorly threaded, 90 and adapted to screw into the interior of the end of said core, said plug also having a retaining groove formed in its unthreaded portion, and an outside jacket surrounding the said core end and the threaded portion of the 95 plug lying therein, said jacket being in engagement with the retaining groove of the plug, and also embodying means engaging the exterior of the said core end.

5. In combination with a tubular winding 100 core, a spindling plug having a threaded engagement with the interior of said core end, and a jacket, mechanically separate from plug, surrounding said core end and longitudinally fixed with relation both to said 105 plug and said core end.

In testimony whereof I affix my signature in presence of two witnesses.

WILLIAM H. MUNROE.
